UNITED STATES PATENT OFFICE.

EDOUARD BELIN, OF PARIS, FRANCE.

AUTOMATIC TELEGRAPHIC OR RADIOTELEGRAPHIC TRANSMITTER.

1,214,989.

Specification of Letters Patent.

Patented Feb. 6, 1917.

Application filed March 12, 1914. Serial No. 824,224.

To all whom it may concern:

Be it known that I, EDOUARD BELIN, a citizen of the Republic of France, residing at Paris, in the Republic of France, have invented certain new and useful Improvements in Automatic Telegraphic or Radiotelegraphic Transmitters, of which the following is a specification.

The object of the present invention is to obtain the automatic sending of signals with the maximum amount of precision for transmitting to a distance by means of telegraphy or radio-telegraphy. It is particularly applicable to the sending of signals controlling telegraphically the relay which controls the radio-telegraphic station transmitter. The general arrangement, which will be described, can equally well be applied to every case in which the operation of the apparatus controlling the sending of the signals is insured at any desired time by means independent of the apparatus. The present invention is described with reference to the sending of signals, or the like from a radio-telegraphic station controlled by an astronomical clock.

On the drawings herewith the general scheme of an installation is shown comprising:

30 Figure 1, the synchronizing of the controlled pendulum by the main pendulum.

Fig. 2, the stylus and its actuating mechanism.

Fig. 3, a detail of the circuit closer for 35 turning the drum 12.

Figs. 4 and 5, an elevation and plan of the arrangement for sending the signals.

Figs. 6 and 7, details of the disk 31 and its associated parts.

40 A is an astronomical clock, the pendulum 1 of which beats seconds, in strictly accurate time. Upon this pendulum 1 a contact 2 is fixed, which at certain moments presses against a flexible arm 3. The time when the contact between the two members will be broken can be accurately adjusted by means of a screw 4, said screw being supported in a bracket 4' secured to the clock casing. This contact, owing to the flexibility of the 45 arm 3 and to the small amplitude of movement of the contact 2, does not appreciably interfere with the free movement of the pendulum 1.

An electrical circuit fed from a battery or 50 the like 5, and passing to the terminals 6, has a short circuit path through the contact

3, 2, and the pendulum 1. Consequently no appreciable current will flow past the terminals 6 except when the contact 3, 2 is open. Therefore at each breaking of the contact 60 between 3 and 2, the current will flow to the terminals 6. 7 is an adjustable resistance. 7' is used to avoid short-circuiting the source of current 5. It is preferable to operate by breaking rather than by closing a circuit, 65 because of certainty of the immediate action, duration and strength of this method and of the current impulse resulting from it. However, it is evident that the use of the arrangement for opening the circuit only 70 represents one method of carrying out the invention.

The pendulum 1 sends at each oscillation an impulse of current into the circuit, the commencement of which is determined very accurately, and the duration of which is itself regulated by the time of the contact 3, 2. The circuit is closed through electromagnets 8, and 8' of the clock B which is to be synchronized by the clock A.

The pendulum 9 carries at its lower end three armatures 10, 10' and 10'' arranged in such manner, that at each of these oscillations the pendulum 9 may be rendered stationary, during a very short time, by the simultaneous attraction of the bobbins 8 and 8' upon the two armatures, which are at that instant opposite the respective cores. This use of the two magnets is found to be practically preferable, but is not essential.

The clock B operates a suitable circuit closer which may be of any type capable of the accuracy required. The distributing apparatus (Figs. 4 and 5) consists of a very accurately formed cylinder 12 which carries in the form of a spiral the relief surfaces controlling the signals to be emitted. The drum may be engraved, but preferably the relief surfaces are in the form of projecting cam shaped surfaces. The cylinder is preferably chosen of such a diameter that the deformation due to expansion by temperature changes is inappreciable and above all to render more appreciable the small differences in diameter due to the hollows or to the projections on its periphery. The cylinder has two stub shafts 13 and 13' supporting it at its ends and allowing it to rotate truly in bushings in two standards 14, 14' carried by a 100 slide base. These two members slide between two guides on the table 15 which in

sure motion perfectly parallel to the cylinder. The axis of the cylinder coincides with that of a shaft 16 which rotates freely. This shaft is threaded upon one half of its length, while the other half is provided with a key-way for engaging with the cylinder. The threaded portion engages with a similar threaded portion within the member 14', so that on the shaft 16 rotating, the members 14 and 14' together with the cylinder 12 are shifted longitudinally, while at the same time the cylinder 12 is caused to rotate by means of a key. This is possible because of the arrangement of supports 16 porting the cylinder by means of the stub shafts 13 and 13' which allow of it rotating freely. This shaft 16 supported by two bearings 17 and 17' also carries:

(1). A drum 18 upon which a gravity or like motor acts by means of the cable 19 which sets the shaft in motion after release;

(2). A ratchet wheel 20, to release the motor;

(3). A friction clutch 21 controlled by an independent electric motor which is used for returning the apparatus through the worm drive. This friction clutch only acts on the cylinder shaft when the whole apparatus is displaced slightly to bring it into engagement. This displacement is produced by the action of an electro-magnet 22 which displaces all the movable parts together with their support by means which will be explained hereafter. In front of the cylinder and fixed upon the frame is the interrupter which transmits to the emitting station the signals carried by the cylinder. The action of the system is as follows:

A current controlled by the clock B passes through the electro-magnet 24 which attracts the pawl 25 whose motion can be regulated by a screw or other means, to release the ratchet wheel 20. This wheel has ratchet teeth upon the side with which the pawl 25 engages. The counterpoise acting through the cable 19 causes the shaft 16 to immediately begin to rotate. Owing to the engagement of the threaded portion of the shaft 16 with the bearings 14' of the cylinder 12, this latter is caused to advance (from left to right in Figs. 4 and 5), while at the same time this cylinder rotates while sliding along the shaft 16. During the displacement and rotation a fixed tracing point or stylus 26 passes over the surface of the cylinder in a spiral path. Upon this spiral path are arranged the cam shaped surfaces representing the signals to be sent and in the actual case shown the stylus 26 will be forced back each time that it passes a cam surface corresponding to a signal. It then breaks contact between the member 27 and the insulated support 28 carrying the

tracing point or stylus in such a manner that the impulse from the circuit due to the relative displacement of the members is sent to the telegraphic or radio-telegraphic transmitter. The succession of operations—namely the breaking of circuit by the movements of the clock, the release of the ratchet device 25—20, the starting of the cylinder, the breaking of the contacts 26 and 27, and the sending of the signals—always taking place in the same order. If these take place at a uniform lag or delay, this can be corrected by a regulation which would allow their action to be advanced and cause the sending of signals to be emitted at the exact predetermined moment when it ought to take place. Before the shaft 16 is rotated, one tooth on the ratchet wheel 20, the clock B will have opened the circuit through the magnet 24 and the rotation will cease when the wheel 20 has moved forward one tooth. The series of signals take place according to the order of the signs traced upon the cylinder during the time that the wheel 20 takes to turn through the sector comprised between two teeth of the ratchet wheel when everything is again ready for the next release of the ratchet allowing further step motion of the cylinder. When the end of the cylinder 12 is reached it is necessary to bring everything back to its exact original position so as to be ready for the next release of the parts.

Fig. 3 shows in detail the means for returning the drum to its original position. At the end of the shaft 16 is loosely mounted a pinion 29 driven from the shaft through the ratchet 30. The pinion 29 engages a toothed disk 31 rotating on an axis 31'. This disk 31 has a groove 33 into which the member 34 can snap under spring action. This member 34 on entering the notch breaks a circuit which starts an electric motor which acting upon the shaft 16 through a pinion of like drive moves this shaft back. The gearing of the pinion 29 with the disk 31 is such that this groove 33 only comes opposite the finger 34 at the end of the time of the useful motion of the cylinder forward; when the shaft 16 turns in the opposite direction the disk 31 is no longer rotated the pawl 30 being out of engagement. The motor will therefore be started at each revolution of the disk 31 so as to bring back the cylinder 12 and raise the counterpoise of the gravity motor. It is only necessary that the return backward should overrun the original starting position a little so as to cause some moving part to strike or otherwise effect in any common way the arm 34' so as to raise the arm 34 from the notch 33 and stop the motor, then the gravity motor will bring it back to the actual starting position. This position is that in which the pawl 25 engages with a

tooth of the ratchet wheel 20, and is reached by a partial rotation of the shaft and the gear wheels 29 and 31. The starting of the disk 31 prevents the contact 34 falling back into the groove 33, while the cam surface 33' is so designed as to prevent the contact 34 locking the disk except when the groove 33 is directly underneath; consequently the motor only comes into circuit again after a complete revolution of the disk 31. Everything depends upon the fact that just after one complete revolution of the disk 31 the finger 34 is moved out of its notch against the action of its controlling spring. Then the motor is automatically stopped and the weight commences its action of bringing the apparatus to its original position. The motor acts on the shaft 16 through the worm gear 22 which is frictionally engaged by the shaft 16 through the clutch 21, the latter being actuated by the magnet 23 through current supplied the magnet simultaneously with the supply current of the motor. By using a friction clutch such as 21, when the motor is stopped by the return of the cylinder to its original position, any jerks on disengagement or of the motor drive are isolated from the system and there is no need of brakes.

At the time set a contact is closed. Now this contact as will be seen from Fig. 5 on being closed causes the operation of the electro-magnet 24. This releases the ratchet wheel 20. The signals are then sent until the relay current is taken off and the ratchet wheel again engages with the pawl on the armature 25. This is the whole operation which is necessary for the sending of the signals. However, it is obvious that after a certain time the drum will come to the end of its course and for this purpose a re-winding arrangement is employed. Such arrangement is illustrated with reference to Figs. 5, 6, and 7. When the cylinder reaches the end of its path that is when it is completely run down, an electric motor is brought into play, while at the same time a relative displacement of the cylinder to the pointer 26 takes place. This allows of the motor turning the cylinder back to its original position, while the pointer 26 is out of the way of the cam-shaped surfaces.

In Fig. 5 the starting of the electric motor also operates the electro-magnet 23 and dis-
55 places the carriage, on which the cylinder 12 and the other parts are fixed, bodily in a longitudinal direction, by this means bringing into operation the friction clutch 21 whereby the motor is brought into engagement with
60 the shaft 16, the displacement being sufficient to move the pointer 26 from the helicoidal path of the cam-shaped surfaces into the recess between these surfaces. On the cylinder reaching the end of its course the
65 contact 34 is operated by the arm 34' see

Fig. 10. This causes the arm 34 to be removed from the slot 33 and thereby the motor is stopped and current no longer passes through the electro-magnet 23. The effect of this is to allow the cylinder to come 70 under the action of the gravity motor until the ratchet wheel 20 is reengaged. This slight movement enables the arm 34 to ride slightly out of the groove 33'. The cylinder is now in its original position and the apparatus is in a condition to repeat its operation.

I declare that what I claim is:

1. An apparatus for transmitting signals at any desired moment by telegraphy, comprising in combination a clock, a contact adapted to be actuated by said clock at a predetermined instant, a cylinder adapted to rotate and having cam shaped surfaces which represent signals, a tracing point in contact with said cylinder and adapted to be actuated by said cam surfaces, said tracing point being adapted to control the transmission of signals, and electromagnetic means for holding the said cylinder adapted to release said cylinder when said contact of said clock is actuated.

2. An apparatus for transmitting signals at any desired moment by telegraphy, comprising in combination a clock, a contact adapted to be actuated by said clock at a predetermined instant, a cylinder adapted to rotate and provided with cam shaped surfaces in a helicoidal path on said cylinder, a tracing point in contact with said cylinder 100 and adapted to be actuated by said cam surfaces, said tracing point being adapted to control the emission of signals, electromagnetic means for holding said cylinder adapted to release said cylinder when said contact of said clock is actuated, and means to provide a longitudinal displacement of said cylinder and said tracing point relative to each other, in order that said tracing point may follow said helicoidal path.

3. An apparatus for transmitting signals at any desired moment by telegraphy, comprising in combination a clock, a contact adapted to be actuated by said clock at a predetermined instant, a cylinder adapted 115 to rotate and having cam shaped surfaces which represent signals, a tracing point in contact with said cylinder and adapted to be actuated by said cam surfaces, said tracing point being adapted to control the transmission of signals, a pawl and ratchet device adapted to hold said cylinder, and an electro-magnet adapted to release said device and allow the cylinder to rotate.

4. An apparatus for transmitting signals 125 at any desired moment by telegraphy, comprising in combination a clock, a contact adapted to be actuated by said clock at a predetermined instant, a cylinder provided with cam shaped surfaces in a helicoidal 130

path on its surface, a shaft having one portion threaded and the other portion provided with a key-way on which the cylinder is fixed, said cylinder being adapted to rotate with said shaft and to be displaced longitudinally relative to said shaft, a gravity motor for rotating said shaft and actuating said cylinder, guides to direct said cylinder in a path parallel to its axis, and a tracing point adapted to be actuated by said cam surfaces on said cylinder and to control the transmission of signals.

5. An apparatus for transmitting signals at any desired moment by telegraphy, comprising in combination a clock, a contact adapted to be actuated by said clock at a predetermined instant, a cylinder provided with cam surfaces in a helicoidal path on its surface, a shaft having one portion threaded and the other portion provided with a key-way on which the cylinder is fixed, said cylinder being adapted to rotate with said shaft and to be displaced longitudinally relative to said shaft, a gravity motor for rotating said shaft and actuating said cylinder, guides to direct said cylinder in a path parallel to its axis, a tracing point adapted to be actuated by said cam surfaces on said cylinder and to control the transmission of signals, and means to electrically wind up said gravity motor and to return said cylinder to its original position.

6. An apparatus for transmitting signals at any desired moment by telegraphy, comprising in combination a clock, a contact adapted to be actuated by said clock at a predetermined instant, a cylinder provided with cam surfaces in a helicoidal path on its surface, a shaft having one portion threaded and the other portion provided with a key-way on which the cylinder is fixed, said cylinder being adapted to rotate with said shaft and to be displaced longitudinally relative to said shaft, a gravity motor for rotating said shaft and actuating said cylinder, guides to direct said cylinder in a path parallel to its axis, a tracing point adapted to be actuated by said cam surfaces on said cylinder and to control the transmission of signals, an electric motor adapted to be actuated when said cylinder has reached the end of its path and adapted to return said cylinder to its original position, and an electromagnet adapted to be actuated simultaneously with said motor to bring said cylinder into engagement with said motor.

7. An apparatus for transmitting signals at any desired moment by telegraphy, comprising in combination a clock, a contact adapted to be actuated by said clock at a predetermined instant, a cylinder adapted to rotate and provided with cam surfaces in a helicoidal path on said cylinder, a tracing point in contact with said cylinder and adapted to be actuated by said cam surfaces,

said tracing point being adapted to control the transmission of signals, electro-magnetic means for holding said cylinder and adapted to release said cylinder when said contact on said clock is actuated, means to provide a longitudinal displacement of said cylinder and said tracing point relative to each other in order that said tracing point may follow said helicoidal path, contacts adapted to be actuated when said cylinder and said tracing point have reached the end of their relative paths, an electric motor adapted to be actuated by said contacts, an electromagnet adapted to be operated by said contacts and adapted to bring said motor into engagement with the shaft of said cylinder, so as to bring said tracing point and said cylinder to their original relative position.

8. An apparatus for transmitting signals at any desired moment by telegraphy, comprising in combination a clock, a contact adapted to be actuated by said clock at a predetermined instant, a cylinder adapted to rotate and provided with cam surfaces in a helicoidal path on said cylinder, a tracing point in contact with said cylinder and adapted to be actuated by said cam surfaces, said tracing point being adapted to control the transmission of signals, electro-magnetic means for holding said cylinder and adapted to release said cylinder when said contact of said clock is actuated, means to provide a longitudinal displacement of said cylinder and said tracing point relative to each other in order that said point may follow said helicoidal path, contacts adapted to be actuated when said cylinder and said tracing point have reached the end of their relative paths, an electric motor adapted to be started when said contacts are actuated, an electromagnet adapted to be operated when said contacts are actuated so as to bring said motor into engagement with the shaft on said cylinder, and to bring said tracing point and said cylinder to their original relative position, and a friction clutch between said motor and said cylinder shaft.

9. An apparatus for transmitting signals at any desired moment by telegraphy, comprising in combination a clock, a contact adapted to be actuated by said clock, a cylinder adapted to rotate and having cam surfaces on a helicoidal path on its surface, a point adapted to be operated by said cam surfaces and to cause the transmission of signals, a ratchet wheel adapted to lock said cylinder and only to be released when said contact of said clock is operated, so as to allow the rotation of the cylinder for the space of one tooth.

10. An apparatus for transmitting signals at any desired moment by telegraphy, a clock, a contact adapted to be operated by said clock, a cylinder adapted to rotate and

having cam shaped surfaces on a helicoidal path on its surface, a tracing point adapted to be actuated by said cam surfaces and to control the transmission of signals, a gravity 5 motor causing said cylinder to rotate and to be given a longitudinal motion, a contact adapted to be closed when said cylinder reaches the end of its path, a motor adapted to be set in motion when said contact is 10 closed, an electromagnet adapted to bring said motor into engagement with said cylinder, a further contact adapted to be opened when said cylinder returns to its original 15 position, and means to release said gravity motor.

11. An apparatus for transmitting signals at any desired moment by telegraphy, com-

prising in combination a clock, a contact adapted to be actuated by said clock, a cylinder having a series of cam-shaped surfaces, 20 a tracing point adapted to be actuated by said cam-shaped surfaces and to control the transmission of signals, a ratchet adapted to hold said cylinder, and a pawl adapted to engage with said ratchet and to be released 25 when said contact of said clock is actuated.

In witness whereof, I have hereunto signed my name this 26 day of February 1914, in the presence of two subscribing witnesses.

EDOUARD BELIN.
